[57] CLAIM

The ornamental design for key bow, as shown and described.

DESCRIPTION

FIG. 1 is a front elevational view of a key bow showing my new design, the rear being a mirror image of that shown;

FIG. 2 is a bottom plan view thereof, the top being a mirror image of that shown;

FIG. 3 is a left side elevational view thereof;

FIG. 4 is a right elevational view thereof;

FIG. 5 is an enlarged fragmentary cross-sectional view thereof, taken along line 5—5 of FIG. 1; and,

FIG. 6 is an enlarged fragmentary cross-sectional view thereof, taken along line 6—6 of FIG. 1.

The broken-line disclosure of the key shank in the views is for illustrative purposes only and forms no part of the claimed design.
